AIRCRAFT ENGINE AND GUN
ASSEMBLY

Marc Birkigt, Bois-Colombes, France

Application March 15, 1934, Serial No. 715,714
In France April 15, 1933

4 Claims. (CL 89—37)

The invention relates to structures including, on the one hand an aircraft engine driving a propeller shaft, for example through reduction gears, said shaft being offset relatively to the crank-shaft of the engine, and, on the other hand, a gun firing through said propeller shaft.

The object of the present invention is to provide an improved structure of that kind.

According to the present invention, the barrel 10 of the firearm extends coaxially throughout the propeller shaft and said barrel is supported by the frame carrying the propeller shaft with a sufficient clearance to permit expansion. Furthermore means are provided for preventing 15 leakage of lubricant at the point where the barrel of the gun passes through said frame.

The invention also includes other features which will be referred to in detail below.

A preferred embodiment of the invention will 20 be hereinafter described with reference to the accompanying drawing in which:—

Fig. 1 shows diagrammatically, partly in section, an assembly constructed according to the invention and including a machine gun.

Fig. 2 shows on a larger scale a detail of the 25 foregoing figure.

It will be assumed in the following description that the machine gun is fitted on an aeroplane engine.

The engine properly speaking is of any suitable type. For example it comprises two rows 30 of cylinders arranged in V form and carried by a common crankcase *a*.

This engine is provided with a reduction gear, 35 for example a spur gear connecting the crank-shaft to a propeller shaft *b* the axis of which passes between the rows of engine cylinders.

This propeller shaft is provided with an axial bore through which can be inserted the barrel of 40 the machine gun above referred to.

This gun is arranged in any suitable way so that when its barrel *c* is engaged in the bore of the propeller shaft, the said gun is located in the free space left by the various parts of the engine.

In order to support the gun in place near its muzzle there is provided in the frame *d* which supports the propeller shaft, or in a member *e* mounted in this frame, an aperture *f* in which 45 the barrel of the gun can be located with a sufficient clearance to permit expansion under the effect of the heat resulting from the firing.

Further, means are provided for preventing the lubricant which serves to lubricate the propeller shaft and the reduction gear from escaping

from the casing at the point where the barrel of the gun enters said casing.

These means advantageously consist of an arrangement of the kind now utilized for preventing losses of lubricant at the point where a rotating shaft leaves a casing, for example by a kind of turbine of which one element rotates near the walls of a fixed element, at least one of these elements having helicoidal grooves running in such direction that when the shaft rotates in the normal direction, the lubricant which tends to escape is forced by the said grooves towards the interior of the casing.

To this end, for example, the portion *e* carries a tubular rabbet *g* having either a cylindrical external wall adapted to be engaged with a very small clearance (sufficient however in order to prevent contact in any case), in a housing *h*, also cylindrical, provided on the inner face of the rear end of the propeller shaft, or having a cylindrical internal wall adapted to enclose the said rear end of the propeller shaft which is also made cylindrical, with a similar clearance.

At least one of the said cylindrical walls is provided with helicoidal grooves *i* and in the case 25 where rabbet *g* is inside the propeller shaft there is advantageously provided on said rabbet *g* an annular groove *j* adapted to receive the lubricant forced back by the helicoidal grooves *i*, a passage being provided for the return of this lubricant to the crankcase.

In order to support the gun in place near the breech the engine advantageously comprises at its rear part a support *k* to which can be connected one of the fixed members at the rear part 35 of the gun.

This support *k* is, for example, given the form of a fork and the gun is provided with a corresponding projection adapted to be connected to the said fork by a spindle or pin *l* which makes 40 the disconnection of the arm particularly simple.

The operation and the advantages of this assembly will be sufficiently obvious from the foregoing for it to be unnecessary to enter into any complementary explanation in regard thereto.

The invention is not limited to the particular constructions described, since variations can be made within the scope of the accompanying claims. Thus, fluid-tightness between the propeller-carrying frame and the barrel of the gun 50 can be ensured through any other suitable arrangement.

What I claim is:—

1. In combination, an aircraft engine, a bearing member fixedly mounted with respect to said

engine, a hollow propeller shaft having a portion extending within and supported by said bearing member, a gun having a barrel extending into said propeller shaft portion, means to support said gun barrel in said bearing member at the rear of said propeller shaft portion with sufficient clearance to permit expansion of the barrel when heated, and means to prevent the passage of lubricant from the outside of the propeller shaft portion to the interior thereof, said last means including a portion of said bearing member extending into the rear end of said propeller shaft portion, having an external surface opposite the internal surface of said hollow propeller shaft portion, and angularly positioned grooves on one of said surfaces.

2. In combination, an aircraft engine, a bearing member fixedly mounted with respect to said engine, a hollow propeller shaft having a portion extending within and supported by said bearing member, a gun having a barrel extending into said propeller shaft portion, means to support said gun barrel in said bearing member at the rear of said propeller shaft portion with sufficient clearance to permit expansion of the barrel when heated, and means to prevent the passage of lubricant from the outside of the propeller shaft portion to the interior thereof, said last means including a portion of said bearing member extending into the rear end of said propeller shaft portion, having an external surface opposite the internal surface of said hollow propeller shaft portion, and angularly positioned grooves on the surface of said bearing member portion.

3. In combination, an aircraft engine, a bearing member fixedly mounted with respect to said

engine, a hollow propeller shaft having a portion extending within and supported by said bearing member, a gun having a barrel extending into said propeller shaft portion, means to support said gun barrel in said bearing member at the rear of said propeller shaft portion with sufficient clearance to permit expansion of the barrel when heated, and means to prevent the passage of lubricant from the outside of the propeller shaft portion to the interior thereof, said last means including a portion of said bearing member extending into the rear end of said propeller shaft portion, having an external surface opposite the internal surface of said hollow propeller shaft portion, and angularly positioned grooves on the surface of said bearing member portion, said bearing member having an annular oil holding groove at the rear end of said propeller shaft portion.

4. In combination, an aircraft engine, a bearing member fixedly mounted with respect to said engine, a hollow propeller shaft having a portion extending within and supported by said bearing member, a gun having a barrel extending into said propeller shaft portion, means to support said gun barrel in said bearing member at the rear of said propeller shaft portion with sufficient clearance to permit expansion of the barrel when heated, a portion of said bearing member extending into the rear end of said propeller shaft portion, and cooperating means on said shaft and the bearing member portion operative through relative rotary movement therebetween to prevent the passage of lubricant from the outside of the propeller shaft portion to the interior thereof.

MARC BIRKIGT.
